CONTAINER FEEDING MECHANISM

John J. Gaynor, Delphi, Ind., assignor of one-half to Arthur I. Risser, Chicago, Ill.

Application April 28, 1934, Serial No. 722,882

22 Claims. (Cl. 226—84)

This invention relates to container feeding mechanism and more particularly to such mechanism as employed in association with a capping machine for positioning containers in cooperative relation with the capping mechanism of the machine.

An object of the invention is to provide such feeding mechanism that will transfer filled containers from a filling machine alternately to the two capping stations of a double head capping machine, whereby the time interval between the filling and capping of the containers is reduced to a minimum. The invention is of particular utility in the capping of containers of chemicals, drugs and like elements in liquid or solid state that are subject to chemical change or deterioration by exposure to atmosphere, as is the case with carbonated beverages.

It is well known that certain chemical elements, such as carbonated beverages, are subject to change or deterioration by agitation. Therefore, it is a further object of the invention to provide such container feeding means that will handle containers of such elements smoothly so as to not cause agitation of their contents.

Another object of the invention is to provide such container feeding means that enables close association of the two capping stations of a double head machine with the container conveying mechanism of a rotary type filling machine, so that a minimum number of containers are interposed in transport from the conveying means to the capping heads of the capping machine.

Another object is to provide such container feeding means of the simplest construction, having a minimum number of moving parts and the mechanism being so arranged as to be easily accessible in the adjustment or replacement of the parts.

Although the invention has to do with the handling of containers, it is also adaptable for handling other elements to be operated upon which are conveyed in single order to a given station and then transferred to two operating tools alternately, which tools may be forging devices, and which elements may be heated parts. In the embodiment of the invention in such mechanism, the heated metal parts would not be subject to much change in temperature in transport. Therefore, in view of the above, the invention is not to be limited to the handling of containers.

Other objects and advantages will become apparent by reference to the specification and the accompanying drawings, in which:

Fig. 1 is a front view of the capping machine embodying the invention with parts broken away, parts in section and showing diagrammatically, in dot and dash lines, a portion of the filling machine.

Fig. 2 is a plan section taken on the section line 2—2 of Fig. 1, with certain parts of the filling machine shown in full lines.

Fig. 3 is a view similar to Fig. 2, with parts shown in changed position.

Fig. 4 is a vertical section taken on the line 4—4 of Fig. 1.

Fig. 5 is an enlarged view of a portion of the container feeding mechanism as shown in Fig. 3.

Fig. 6 is a sectional view taken on the section line 6—6 of Fig. 5.

Referring to Figs. 1, 2 and 4, the filling machine A, a portion only of which is somewhat diagrammatically illustrated, is of a well known type in the rotary class, and as more clearly shown and described in my Patent No. 1,958,476, of May 15, 1934. The filling machine comprises a circular horizontally rotating filling tank 2, suitably mounted on a central pedestal, not shown. Arranged equally spaced about the axis of the tank 2 and depending from the edge portion of the tank, are vertically reciprocably mounted filling heads 3, which are adapted to dispense liquid from the tank upon being raised therein, the filling machine has means for conveying containers or bottles 4 under the filling heads in cooperative relation therewith. Said conveying means includes a plurality of vertically disposed plungers 5 equally spaced about the axis of the tank so that each plunger is below and coaxial with a filling head. The plungers 5 are reciprocably mounted in bearings 6 in the periphery of a circular lateral support extension 7, of the pedestal supporting the tank, whereby the plungers 5 rotate with the tank. Secured on the top end 40 of each plunger 5 is a container support stirrup 8, having an outwardly open yoke 9 for receiving and positioning under its respective filling head, a container or bottle 4 to be filled.

The tank 2 and support extension 7 of the filling machine rotate continuously in clockwise direction, as viewed in plan, and as the filling machine plungers 5 cross the station, indicated by the dot and dash line B—B in Fig. 1, the bottles are placed in the stirrups by automatic means, not shown, and at which station the plungers 5 are in lowered position with the filling heads thereover spaced above the bottles thereon. The plungers 5 are then moved to raised position, by suitable means, not shown, causing the

bottles thereon to enter and raise the filling heads thereover into the filling tank, and in which position the plungers remain during considerable movement of the tank to effect the filling of the bottles. The filled bottles are then lowered by the plungers 5, actuated by suitable means, before reaching the receiving station B—B, and are then transferred to the capping machine C, embodying the invention.

10 After the plungers 5 reach their lowered position, the filled bottles thereon are transferred, or deflected outward from the stirrups onto a bottle support in the form of a table 10 whose supporting surface is in the plane of the supporting surfaces of the stirrups in lowered position. The table is mounted upon a base or pedestal 11, extending upward from which are spaced apart uprights or rods 12 and 13 respectively extending through bosses 14 and 15 depending respectively from the left and right hand ends of the table. Any suitable means may be provided for holding the table in vertical adjusted positions on the uprights, such as the set bolts 16 passing through the bosses. The outer edges 17 of the stirrups are formed arcuate concentric with the filling machine tank, and the adjacent edge 18 of the table is formed arcuate concentric with the stirrup edges and in close relation therewith.

Upon being initially positioned on the table 30 at the station indicated by the dot and dash line E—E, Fig. 2, the bottles are alternately transferred by feeding means to two separate stations indicated on the table by the crosses F and G, in cooperative relation with capping mechanism 35 later described.

For feeding or transferring the bottles from the filling machine stirrups onto the table and directing or guiding same to said separate stations F and G, a central bottle guide member or 40 partition 19 is mounted on the table, arranged inward of and in line with the initial station of a bottle on the table and the axis of the filling machine tank and support 1. Cooperating with said central partition on either side for directing 45 bottles from said initial station to said separate stations F and G, and slightly therebeyond, are respectively arcuately formed directing members in the form of rails 20 and 21 converging from said separate stations to the initial station of 50 the table. Each rail has a short base portion 22 for mounting on the table near its edge opposite its edge 18, and from which base the rail extends inward over the table with a bottom portion 23, in the form of a lateral reinforcing flange, 55 spaced thereabove, to allow passage therebetween of mechanism later described. The guide rail 20 continues into an end portion 24 extending angularly beyond the initial or common station of the bottles on the table and to project over 60 the path of the stirrups for deflecting the containers or bottles therefrom and onto the table. The inner end 25 of the rail 21 is spaced from the rail end portion 24 so as to allow the bottles being deflected to pass therebetween.

65 For transferring the bottles from the common station E—E on the table to said separate stations F and G, alternately, an operating carrier member or slide in the form of a bar 26 is mounted to move back and forth, or reciprocate 70 transversely under the path of the bottles in transport from the common station to said separate stations. The slide bar 26 is reciprocably mounted in a guide groove 27 in the table to intersect its edge 18 at the common station, the 75 bar being retained in the groove flush with the

table surface by bolts 27a secured under the bar and received in slots 27b in the groove bottom. The bar thus forms a support for the bottles being transferred from the stirrups to the table. Mounted on the slide bar 26 is a container pusher member in the form of a finger 28 pivotally mounted on a vertical pin 29 secured on the bar near the table edge 18 and to extend neutrally inward toward the table and at right angle to the bar. The finger 28 has limited oscillatable movement from either side of its neutral position which is effected by a pin projection 30 depending from the finger and received in an elongated slot 31 in the bar 26, which slot has end walls 32 engaged by the pin 30 in limiting the movement of the finger.

The slide bar 26 has a throw a little greater than the distance between the axes of the separate bottle positioning stations F and G, and the finger 28 is so arranged on the bar whereby the 20 bottles are initially placed on the table intermediate its limits of movement with the bar and in the path thereof. The bar 26 is so operated by operable connection with the filling machine whereby, when the finger is moved toward the left with the bar (see Fig. 2), a bottle is placed in its path from a stirrup, whereupon the finger is caused to engage the bottle initially at its pivotal connection and in contact with the trailing side of the bottle. By this engagement with 30 the bottle the finger is caused to be shifted about its pivot to extend away in angular relation with the bottle, whereby on continued movement of the bar the finger urges the bottle along the guide rail 20 by deflection, in that the bottle rides along the finger as well as the rail until the finger reaches its limit of movement with the bar, at which point the bottle is engaged by the end 33 of the finger in being positioned at the station F, in which position the parts are seen in Fig. 3. 40

Upon the return movement of the finger with the bar 26, and toward the right (see Fig. 3), a succeeding bottle has been placed in its path which is transferred to the station G, by the finger in a manner similar to its action in transferring the preceding bottle to its station, where in the succeeding bottle is urged along the rail 21 to the station G.

Before the pivotal end of the finger engages a bottle at the common station on the table, the 50 bottle has been positioned so that its axis is beyond the path of said pivotal end so that the end will engage the trailing side of the bottle. This placing of the bottle is effected by the trailing side 34 of the stirrup yokes being extended into 55 an outwardly flaring end portion 35 which cooperates with the end portion of the rail 20, which end portion 35 passes very close to the outer edge of the slide bar 26. This yoke end portion 35 also cooperates in directing a bottle, 60 being urged by the finger toward the guide rail 21, into deflectable relation with said rail end portion 25.

Above the capping stations F and G on the 65 table are capping mechanisms or capping heads 36 and 37 respectively, hereinafter described, which heads are caused to apply caps or crowns 38 to bottles positioned in their respective stations and upon the initial return movement of the finger 28 with the slide bar.

To positively eject the capped bottles from the stations F and G, before succeeding bottles are positioned therein, bottle ejecting members or deflectors 39 and 40 are provided which are operably connected with the slide bar 26 and which 70

upon a complete cycle of movement of the bar are caused to respectively cooperate with the partition in deflecting the capped bottles from the stations F and G. Each deflector comprises a bracket portion 41 mounted on the bar 26 to extend over the table, the two brackets being arranged on the ends of the bar and spaced equally from the finger. Each bracket portion 41 has a cam portion or bottle deflecting formation 42 extending inwardly toward the stations, whereupon at the limits of movement of the bar toward the right and left, as seen in Fig. 2, the deflectors 39 and 40 respectively cooperate with the central partition 19 in ejecting the capped bottles from the stations F and G by engagement of the cam portions of the brackets with the bottles. By this arrangement of the deflectors a capped bottle is ejected from one capping station upon the positioning of a bottle at the other station.

The slide bar 26 is in driven connection with the filling machine, so as to be in the time relation as outlined, by means of a ring gear 43 mounted on the periphery of the lateral extension 7 outside of the bearings 6 of the filling machine, which gear meshes with a pinion 44 disposed below the table and mounted on the lower end of a vertical drive shaft 45 rotatably mounted in a bearing 46 in the table at said end and extending upward of the table to be rotatably mounted in a bearing 47 on a bracket 48 mounted on a horizontal capping mechanism support member 49 mounted for vertical adjustment on the uprights 12 and 13 which pass through supporting bearings 50 and 51 respectively at the ends of the support, there being set bolts 52 threaded into the bearings for holding the support on the uprights in adjusted positions. On the drive shaft 45 is a bevel gear 53 connected for vertical adjustment thereon with the support member 49 by means of a key 54, mounted on the bearing 47 of the bracket 48, which key is received in a peripheral groove 55 in the hub of the gear. The gear 53 is connected to rotate with the drive shaft by means of key connection with the elongated keyway 56 in the shaft. Meshing with the bevel gear 53 is a bevel gear 57 mounted on the rear end of a horizontal driven shaft 58 rotatably mounted centrally in a bearing 59 in the horizontal support member 49 extending transversely therethrough. On the outer end of the driven shaft 58 is mounted a double crank member 60 having an outer crank pin 61 for pivotal connection with one end of a connecting link 62 whose other end is pivotally connected to the free end of an oscillating arm 63 mounted on the outer end of a rock shaft 64 rotatably mounted centrally in the bearing 65 of a bracket 66 mounted on the table. On the inner end of the rock shaft is a depending rocker arm 67 in pivotal connection with a lug 68 through the intermediation of a connecting link 69, which lug is formed on the bottle deflector bracket portion of the deflector 40. The said gears, cranks and arms are so proportioned as to effect the proper timed relation of the filling machine and transferring mechanism, wherein the slide bar 26 completes one half of its cycle of movement, or movement in one direction, upon movement of the bottles in being conveyed on the filling machine, a distance equal to the spacing of the filling machine bottle support plungers. It may be stated that the ring gear 43 also serves as an operable connection with gear driving means (not shown)

for rotating the support extension 7 as well as the tank mounted thereover and capping mechanism which will be hereinafter described.

The capping heads 36 and 37 comprise respectively similar hollow cylinders or plungers 70 and 71 vertically disposed above the table and respectively positioned coaxial with the separate bottle capping stations F and G. Each plunger of the heads extends through and is reciprocably mounted in a bearing 72 in the support member 49. The capping heads are of the type disclosed in my Patent No. 1,958,476, previously mentioned, which are adapted to apply such caps as the well known bottle stoppers or crowns. Therefore a detailed description of the heads will not be dwelt upon. However, it may be stated that each plunger 70 and 71 has a cap receiving recess 73 for positioning a cap central with the axis of the plunger with its open side facing downward, and the cap being in cooperative relation with suitable constricting means, as shown in said patent, for applying the cap onto a bottle upon lowering of the plunger thereon.

The recesses of the capping head plungers open outward in converging relation for cooperative register with the discharge end 74 of a horizontally oscillating cap supply magazine 75, of the gravity feed type; when the capping heads are in raised position. Each capping head is so operated that upon the positioning of a bottle thereunder, it is lowered thereon to apply the cap positioned in its recess, during which time the other capping head is held in raised position with its recess in register with the magazine discharge end for receiving a cap.

The magazine is in the form of a chute with the caps or crowns guided therein the edgewise single order, and the chute being arcuately formed with a top vertical end portion 76 which is pivotally mounted for horizontal movement on a pivot pin 77 depending from a cap feeder device 78, said top end being arranged to be in constant register with the lower discharge end 79 of the feeder device. The feeder device is mounted on a bracket 80 mounted on the horizontal support 49 to extend upward thereof and over the capping heads. The chute or magazine extends arcuately downward and inward toward the capping heads and terminates in its discharge end which is mounted, so as to be guided in the plane of the recesses of the heads when same are in raised position, to project in an arcuate groove 81, concentric with the pivot of the magazine and formed in the lower part of the support 49. In the bottom of the groove are cap passage ways 82 through which the caps pass from the magazine and into the recesses of the capping heads. The bottom portion 83 of the groove 81 serves to hold the caps in the magazine during movement therebetween the capping heads.

The capping heads and magazine are so operated that when a head is in raised position the magazine discharge end is moved into register with its cap recess, and whereupon the other head is moved to lowered position in applying the cap therein to a bottle thereunder. The means for so operating said elements includes an actuator bar 84 extending along the front side of the support member 49. The bar 84 is reciprocably mounted between rollers 85 of two spaced pairs thereof, which rollers are mounted on bolts 86 secured in the support 49, which bolts support strips 87 outside the pairs of rollers for holding the bar 84 guided on the rollers.

The actuator bar 84 is operably connected with the capping heads for operating same in the manner described, by means of cam formations or downwardly converging spaced cam slots 88 and 89 which are formed in the top portion of the bar, and which are adapted to respectively alternately receive rollers 90 and 91 at the lower ends of the depending rocker arms 92 and 93 respectively for operating the heads through intermediation of the arms, and upon a complete cycle of reciprocation of the bar. The rocker arms 92 and 93 are respectively mounted on the front ends of horizontal shafts 94 and 95 which are respectively mounted in bearings 96 and 97 mounted in upward extensions of the support 49 and between which the heads are disposed. On the rear end of the shaft 94 is an arm 98 whose free end is in pivotal connection with the top end of the capping head plunger 71 of the head 37, for operating the head upon oscillation of the rocker arm 92. Extending from the hub of the rocker arm 93 is an arm extension 99 whose free end is in pivotal connection with the top end of the capping head plunger 70 for operating the head upon reciprocation or oscillation of the arm 93. The cam slots 88 and 89 are so spaced apart that when the actuator bar is in neutral position, both arms 92 and 93 depend in converging relation with their rollers resting on the top surface of the bar extending away from the slots in holding the heads in raised position, the portion 100 of the bar between the cam slots extends upward into the paths of the rocker arm rollers to enable engagement of the rollers in their respective slots upon movement of the bar in either direction.

Under the actuator bar 84 and directly below the portion 100, is a depending portion 101 of the bar within the under side of which is an elongated slot or notch 102 for receiving a roller 103 on the top portion of the discharge end of the cap magazine, for operating the magazine in timed relation with the capping heads.

The actuator bar 84 is so operated in timed relation with the transferring means, or slide bar 26, that, as a bottle is being positioned in one of the capping stations, the capping head thereover is being lowered to apply the cap thereon. To this end the actuator bar is reciprocated by the double crank arm 60, on whose central crank pin portion 104 is pivotally connected one end of a resilient link 105 whose other end is in pivotal connection with the outer end of the actuator bar, as at 106.

The resilient link is employed to maintain uniformity of pressure of the capping heads upon the bottles as well as preventing breakage of the bottles in the event bottles become dispositioned under the heads when same are lowered. It is thought that a detailed description of the resilient link is not necessary, however the link as shown forms part of the subject matter of my prior copending application Ser. No. 684,236.

Although other means may be employed for feeding caps to the magazine, the feeding device shown includes a cap hopper 107 in which is contained operated cap feeding mechanism, which mechanism is operated by a horizontal shaft 107a mounted to extend through the hopper and having a sprocket gear 108 on its rear end connected to a sprocket gear 109 on the hub of the double crank, through the intermediation of the sprocket chain 110, for operating the shaft.

The organization of the capping mechanism, cap feeding mechanism and the resilient linkage herein disclosed, is broadly disclosed and claimed

in my said Patent No. 1,958,476, and said organization inclusive of the capping mechanism operating means is disclosed and broadly and specifically claimed in my following application for patent on Capping machines, Ser. No. 727,292, filed May 24, 1934.

Having thus described my invention, I claim:

1. The combination with a capping machine having container supporting means, means for conveying containers onto the supporting means to a common station and means for directing containers from said station to two separate stations, of means for alternately transferring containers from said common station to said separate stations including a carrier element movable back and forth transversely to one side of the paths of the containers to said separate stations, and container deflecting means carried on said carrier for cooperating with the directing means, wherein the deflecting means includes a finger pivotally mounted on the carrier for limited movement alternately into cooperative deflecting relation with the containers upon said movement of the carrier.

2. The combination with a capping machine having container supporting means, means for conveying containers onto the supporting means to a common station and means for directing containers from said station to two separate stations, of means for alternately transferring containers from said common station to said separate stations including a carrier element movable back and forth transversely to one side of the paths of the containers to said separate stations, and container deflecting means carried on said carrier for cooperating with the directing means, wherein the deflecting means includes a container pusher element mounted movable back and forth on the carrier and arranged whereby upon said movement of the carrier it is moved alternately thereon into cooperative deflecting relation with the containers by engagement therewith.

3. The combination with a capping machine having container supporting means, means for conveying containers onto the supporting means to a common station and means for directing containers from said station to two separate stations, of means for alternately transferring containers from said common station to said separate stations including a carrier element movable back and forth transversely to one side of the paths of the containers to said separate stations, and container deflecting means carried on said carrier for cooperating with the directing means, wherein the carrier element comprises a slide over which the containers pass.

4. The combination with a capping machine having container supporting means, means for conveying containers onto the supporting means to a common station and means for directing containers from said station to two separate stations, of means for alternately transferring containers from said common station to said separate stations including a carrier element movable back and forth transversely to one side of the paths of the containers to said separate stations, and container deflecting means carried on said carrier for cooperating with the directing means, wherein the container supporting means comprises a table having a guideway in its supporting surface, wherein the carrier element comprises a slide bar reciprocably mounted in the guideway flush with the table surface and where-

in the deflecting means includes a container pusher element mounted on the slide.

5. The combination with a capping machine having a table for supporting containers, a container conveyor movable alongside one edge of the table, means for directing containers from the conveyor and onto the table to a common station and two opposed container guides for directing containers from said station to two separate stations inward on the table, of a slide bar reciprocably mounted alongside said table edge portion to be flush with its supporting surface, and a container pusher element mounted on the bar for alternately cooperating with the guides 10 in transferring containers to said separate stations.

15. The structure as defined in claim 5, wherein in the pusher element comprises a finger pivotally mounted on the bar for limited horizontal movement thereon to extend inward of the table.

20. The combination with a capping machine having container supporting means, means conveying containers onto the supporting means in single order, means for directing the conveyed 25 containers to two separate stations on the supporting means and means for alternately transferring the conveyed containers to said separate stations, of means associated with said transferring means and operable upon a container being positioned at a station for ejecting a container from the other station including a carrier element movable back and forth transversely to one side of the paths of the containers to said 30 stations and arranged to cooperate with the supporting means, and container ejecting means carried on the carrier and arranged to be moved thereby into cooperative relation with the directing means.

35. The structure as defined in claim 7, wherein the ejecting means comprises two container deflecting members mounted on the carrier and each arranged to have deflecting engagement with a container at a separate station upon said movement of the carrier.

40. The structure as defined in claim 7, wherein the carrier element comprises a slide over which the containers pass supported thereon.

45. The structure as defined in claim 7, wherein in the carrier element comprises a slide over which the containers pass and wherein the ejecting means comprises two container ejecting members mounted on the slide and each formed with a cam portion for deflecting engagement with the containers of a separate station upon said movement of the carrier.

50. The structure as defined in claim 7, wherein in the carrier comprises a slide over which the containers pass and wherein the ejecting means comprises two container ejecting members mounted on the slide and each formed to have deflecting engagement with a container at a separate station upon movement of the slide and wherein the transporting or transferring means 55 comprises a container pusher member mounted on the slide and adapted to urge the conveyed containers alternately into cooperative relation with the directing means of the separate stations.

55. The combination with a capping machine having a table for supporting containers, a container conveyor movable alongside one edge of the table, means for directing containers from said conveyor and onto the table to a common station, two opposed guides for directing containers from said common station to two separate stations, of a slide bar reciprocably mounted

along said table edge to be flush with its supporting surface and to extend under said guides, a pusher member mounted on the bar adapted to move back and forth across the paths of the containers upon said movement of the bar in 5 urging the containers alternately into cooperative relation with the two guides of said stations, and two container ejecting members mounted on the bar and disposed on either side of the pusher and each ejecting member having a cam 10 portion for engaging a container at a separate station in ejecting same upon said movement of the bar.

15. The structure as defined in claim 12, wherein in the pusher member comprises a finger pivotally mounted for limited movement on the bar to extend inwardly of the table.

20. In combination, container conveying means, two capping heads and means for transporting containers from the conveying means into cooperative relation with the heads alternately including a reciprocably mounted slide bar over which the containers pass transversely from the conveying means to the capping heads and a container pusher member mounted on the bar 25 for alternately cooperating to urge the containers into cooperative relation with said heads upon said movement of the bar.

25. The structure as defined in claim 14, wherein in the pusher member comprises a finger pivotally mounted on the bar for limited movement to extend in deflecting relation with the containers upon engagement therewith.

30. The structure as defined in claim 14, including means operably connected with the bar 35 and operable upon a container being urged by the pusher into cooperative relation with a head for ejecting the container out of cooperative relation with the other head.

35. In combination in a capping machine, a 40 container supporting table, two opposed spaced apart guide rail portions mounted over the table each adapted to cooperate in positioning a container at a separate station on the table, a carrier slide bar reciprocably mounted on the table 45 to be flush with its supporting surface and to extend along an edge portion thereof, a finger pivotally mounted for limited movement on the bar to extend inwardly of the table and arranged whereby at each limit of its movement on the bar 50 it is in cooperative relation with a separate guide rail in positioning a container at a station upon each limit of its movement with the bar.

45. The combination with a machine of the class described having means for conveying containers to a common station, of means for alternately transferring the containers from said station to two separate stations including a container deflector element mounted movable back and forth across said common station and mounted shiftable to two different positions during its said movement and arranged whereby in each of its said positions it is in cooperative deflecting relation with a container at said common station, wherein there is a carrier element mounted movable back and forth upon which the deflector is mounted shiftable to said two positions, and wherein the deflector is shifted into said cooperative relation with a container by engagement therewith upon said movement of the carrier. 55

55. The combination with a machine of the class described having means for conveying containers to a common station, of means for alternately transferring the containers from said station to two separate stations including a con- 75

5 tainer deflector element mounted movable back and forth across said common station and mounted shiftable to two different positions during its said movement and arranged whereby in each of its said positions it is in cooperative deflecting relation with a container at said common station, wherein there is a carrier in the form of a slide mounted movable back and forth under a container at said common station and upon which 10 slide the deflector is mounted shiftable to said two positions.

15 20. The combination with a machine of the class described having means for conveying containers to a common station, of means for alternately transferring the containers from said station to two separate stations including a container deflector element mounted movable back and forth across said common station and mounted shiftable to two different positions during its 25 said movement and arranged whereby in each of its said positions it is in cooperative deflecting relation with a container at said common station, wherein there is a carrier element mounted movable back and forth under a container at said common station, wherein the deflector element is in the form of a finger pivotally mounted on said carrier for limited oscillatable movement to said two positions, and wherein the finger is moved into said cooperative relation with a container by engagement therewith upon said movement of the carrier.

30 35 21. The combination with a machine of the class described having means for conveying containers to a common station, of means for alternately transferring the containers from said station to two separate stations including a con-

5 tainer deflector element mounted movable back and forth across said common station and mounted shiftable to two different positions during its said movement and arranged whereby in each of its said positions it is in cooperative deflecting relation with a container at said common station, wherein there is a horizontal slide bar mounted longitudinally reciprocable and arranged whereby the containers pass thereover in supported relation thereon from the common station to the 10 said separate stations, and wherein the deflector element comprises a horizontal finger pivotally mounted at one end on the bar near its edge initially approached by the containers for limited oscillatable movement over the bar, said 15 finger arranged so as to be moved or shifted into said cooperative deflecting relation with a container by engagement therewith upon said movement of the slide bar.

20 25 30 35 22. The combination with a machine of the class described having means for conveying containers to a common station, of means for alternately transferring the containers from said station to two separate stations including a container deflector element and means for moving the deflector back and forth across said common station including an operating member with which the element is shiftable connected whereby the element is shifted to two different container deflecting positions by engagement with two containers successively during its back and forth movement in alternately deflecting the containers from said common station to said separate stations.

JOHN J. GAYNOR. 35
